VAN VECHTON RIESBERG, OF PHILADELPHIA, PENNSYLVANIA, ASSIGNOR OF ONE-HALF TO FRANK H. DOUGHERTY, OF PHILADELPHIA, PENNSYLVANIA.

FOUNTAIN-PEN.

1,171,652.

Specification of Letters Patent. Patented Feb. 15, 1916.

Application filed March 17, 1914. Serial No. 825,436.

To all whom it may concern:

Be it known that I, VAN VECHTON RIESBERG, a citizen of the United States, and a resident of the city of Philadelphia, county 5 of Philadelphia, and State of Pennsylvania, have invented certain new and useful Improvements in Fountain-Pens, of which the following is a specification, reference being had to the accompanying drawing.

10 Among the principal objects of my invention are to provide a new and improved fountain pen in which the flow of ink shall be constant when the pen is in operation; which shall be cheap and simple to construct, and which may, therefore, be sold at a low price; which shall present a neat and attractive appearance; which shall have no tendency to clog up; which may be readily cleaned, and which shall be void of complicated or intricate mechanism or parts.

25 Further objects of my invention are to provide such a fountain pen which shall be durable in operation; which shall consist of a minimum number of parts; which may be readily filled with ink, and which shall have no tendency to overflow or blot either when in or when not in operation.

30 My invention further includes all of the various other novel objects and features of construction and arrangement hereinafter more definitely specified.

In the accompanying drawing in which is shown a fountain pen embodying one form 35 of my invention, Figure 1 is a central longitudinal section of such a pen, together with its cover, a portion of the pen being shown in elevation, and Fig. 2 is a fragmentary central longitudinal section considerably enlarged, clearly illustrating certain details 40 of the device.

That form of my invention shown in the drawing may consist of an elongated, preferably cylindrical barrel 1, of suitable size and shape and formed of suitable material, 45 providing the ink reservoir 2 in its interior. One end of the reservoir may be closed by a suitable cap 3, removably attached to the barrel 1 in any suitable manner. In the drawing the cap is shown as provided with 50 internal threads 5 at its open end suitable for engagement with other threads provided upon the exterior of the barrel 1 adjacent its open end, the external diameter of the barrel being slightly reduced at that 55 point for the purpose, so that when the cap

3 is screwed in place, the exterior of the barrel and cap will present a substantially uniform surface. If desired the exterior of the barrel and cap may be slightly tapered toward the end of the cap, as shown in the 60 drawing, in such manner that the cover 7, the interior of which may be provided with a similar taper, may be slipped over the cap and barrel and be frictionally maintained thereon in the well-known manner when the 65 pen is in operation, the cover thus serving to somewhat elongate the pen, and affording a better grip for the hand of the user.

The exterior of that end of the barrel opposite to the end at which the cap 3 is attached, may preferably be reduced in diameter, thereby providing an annular shoulder 10, beyond which the exterior of the barrel is tapered gradually inward, thus forming a somewhat extended point 12, as 75 clearly shown in Fig. 2, the extreme outer end thereof being shaped to provide a seat or cup 14, adapted for the reception of a substantially spherical element or ball 15, which may preferably be formed of mate- 80 rial of considerable hardness.

The cup 14 upon the end of the pen barrel may preferably be of such size as regards the ball 15 that it will extend well up on the sides of the ball but will not extend far 85 enough to reach the point of greatest diameter thereof, although the proportions of the ball and the cup may be regulated in practice as desired to produce the best results.

90 A substantially conical cap 20, preferably formed of metal, hard rubber or other suitable material, is adapted to rest over the point 12 of the barrel, and to be secured in place thereon preferably by suitable threads 95 on its interior engaging with similar threads 22 formed upon the reduced portion of the barrel 1, the face of its larger end preferably engaging the face of the shoulder 10. The walls of the cap 20 may preferably be tapered or thinned down toward its smaller end, which may be provided with a suitable opening of slightly smaller diameter than the diameter of the ball 15, so that when the cap 20 is in position upon the barrel 1, and the ball 15 resting in the cup 14, as clearly shown in Fig. 2, a considerable portion of the ball will project somewhat beyond the smaller end of the cap 20. If desired the taper of the exterior of the point 100 110

12 of the barrel 1 may be slightly greater than that of the interior of the cap 20, whereby a small space 25 will be provided between the interior of the cap and the exterior of the barrel, although if desired the tapers may be made the same so that there will be no space between these parts of the device.

If desired the exterior of the barrel 1 at 10 that end thereof nearest the ball may be tapered in a manner similar to that already described in relation to the other end of the pen, so that when the cover 7 be slipped over the end of the pen it will be retained 15 thereon by friction in the ordinary manner. If desired, however, other means for maintaining the cover 7 in position upon either end of the pen barrel may be provided such as screw threads or other equivalent 20 means.

The interior walls of the barrel 1 may preferably be so formed as to substantially follow the contour of the exterior walls thereof, and the reservoir 2 in the interior 25 of the pen will therefore be of greatest diameter at the point of greatest diameter of the pen and will taper toward the point of the pen as clearly shown in Fig. 2, its end adjacent the ball 15 being of relatively 30 small diameter. Leading from the reservoir 2 to the interior of the seat 14 is a suitable duct 27, preferably in axial alignment with the central longitudinal axis of the pen, whereby the ink or other fluid 35 contained within the reservoir will be conducted to the surface of the ball 15.

The operation of the device is as follows: Ink or other fluid may be introduced into the reservoir 2 by detaching the 40 cap 3, after which operation the cap 3 may be replaced in the position shown in Fig. 1. The fluid will now be conducted, when the pen is maintained in a position suitable for writing, to the surface of the ball 15 45 by means of the duct 27, and from thence to the surface of the paper by the rotation of the ball when the pen is in operation, the friction between the surface of the ball and the paper being sufficient to rotate the 50 former. It will be understood that the ball is maintained between the surface of the cup 14 and the interior of the cap 20 with just sufficient pressure so that it will rotate when it traverses the paper, but not sufficiently loosely to permit the ink to flow 55 from the duct 27 over the surface of the ball and between it and the interior of the cap 20 when the pen is merely held with the ball 15 pointing downwardly. In other 60 words, when the pen traverses the paper ink will be, so to speak, "drawn down" by the rotation of the ball, but will not flow readily over the surface of the ball unless the same be rotated. It will be understood 65 that a certain longitudinal adjustment of

the relation between the cap 20 and the surface of the cup 14 will be permissible in practice depending upon the consistency of the ink or other fluid used in the pen, and it is therefore considered that the threads 22 70 should be made of comparatively fine pitch in order to permit of an accurate adjustment of the cap 20 upon the barrel, or, if other means of securing the cap in position are utilized, such means should be designed 75 so as to permit of a similar longitudinal adjustment of the cap 20. It is not intended, however, in the commercial form of my invention that the relation between the cap 20 and the barrel 1 shall be constantly 80 varied by the user, but that the pens shall be properly assembled and adjusted at the factory, and that the cap 20 shall not be thereafter disturbed from its adjusted position except to insert a new ball or when 85 exceptional or unusual conditions of use are encountered. It will be further understood that the rotation of the ball will be facilitated by the lubricating effect of the ink or other fluid, and that in consequence the 90 wear between the ball and the various surfaces contacting with it will be practically negligible. Moreover, that I do not desire to limit myself to the precise details of construction and arrangement of the various elements of my invention which I have herein 95 illustrated and described, nor do I desire to limit myself to any specific materials for use in the construction of the device, as it will be evident that any suitable materials 100 may be employed and that various changes in the details of construction and arrangement may be adopted without departing from the spirit and scope of the invention 105 as defined in the appended claims.

Having thus described my invention, I claim and desire to protect by Letters Patent of the United States:

1. In a fountain pen the combination with a substantially cylindrical elongated 110 barrel having one end tapered to form a point, of a substantially conical cap operative to cover said point and spaced therefrom adjacent said point, threads upon the exterior of said barrel operative to engage 115 with threads upon the interior of said cap, a cup formed upon the end of said barrel, a ball in said cup, and means operative to conduct a fluid from the interior of said barrel to the surface of said ball and to the space between said cap and said barrel, said conical cap being operative to maintain 120 said ball within said cup.

2. In a fountain pen the combination with a substantially cylindrical elongated 125 barrel forming an ink reservoir and tapered at one end, of means operative to close the other end of said barrel, a substantially cone-shaped cap removably positioned upon said barrel and spaced therefrom adjacent 130

its extremity and having an opening at its smaller end, a ball, a cup-shaped seat for said ball upon the tapered end of said barrel, and a duct leading from said reservoir to the surface of said seat, said cone-shaped cap being operative to maintain said ball in rotatable relation with said seat and said duct to conduct a fluid to the space between said cap and said barrel.

3. In a fountain pen, the combination with a substantially cylindrical elongated barrel having one end tapered to form a point, of a cap interiorly tapered less sharply than said barrel and positioned over said point whereby a space is left between said point and said cap, a depression

formed on the end of said point, a ball in said depression having its surface extending into said space, and means operative to conduct fluid from the interior of said barrel to said ball and thence to said space whereby a body of said fluid will be constantly maintained within said space and in contact with said ball.

In witness whereof I have hereunto set my hand this 16th day of March, A. D. 1914.

VAN VECHTON RIESBERG.
